C. H. Fonde
Dredging Mach.
No 12,720.

Patented Apr 17-1855

UNITED STATES PATENT OFFICE.

CHARLES H. FONDÉ, OF MOBILE, ALABAMA.

DREDGING-MACHINE.

Specification of Letters Patent No. 12,720, dated April 17, 1855.

To all whom it may concern:

Be it known that I, CHS. H. FONDÉ, of the city and county of Mobile and State of Alabama, have invented a new and useful

5 Improvement on the Dredging-Machine of Fondé and Lyons, for which a patent was granted on the 21st of March, 1854; and I do declare that the following is a full, clear, and exact description of the construction 10 and operation of the same; reference being had to the annexed drawings, making a part of this specification, in which—

Figure 1, is a side view; Fig. 2, a deck plan; Fig. 3, a transverse section.

15 The improvements here shown and set forth consist of three distinct devices.

The first device has for its object the keeping of the wheel always in gear with the engine while it is raising and lowering 20 and consists of the radius bar marked A and the sliding carriage marked B, which carries the pinion shafts C. The radius bar is connected with and works upon the main shaft at D. Now it will be seen that if the 25 excavating wheel is raised the radius bar will draw the sliding carriage upon the slides, E, thus keeping the pinions in gear with the large cogged perimeter of the excavating wheel notwithstanding the difference 30 in their relative positions.

The second device consists of a latch whose peculiar form and adjustment though very simple has a self acting and double capacity not only for holding the lid or bottom 35 of the bucket until it is struck by the tipper, but also of toppling over by its own gravity and latching or taking hold of the lid again before the bucket again enters the water, thereby dispensing with the use of 40 springs, this latch is marked F.

The third device has for its object the discharging of an excavating wheel laterally or over the side of the boat, or on both sides at once. Which has never before been done, 45 and consists of an arrangement of two chutes or sluice ways, G, G, which form an

apex under the discharging tipper and conveys the excavated matter into the scows, which lie alongside, instead of across the stern as heretofore. 50

I do not here claim the excavating wheel with buckets across the periphery nor the tilting tipper for discharging the same nor the manner of applying power to the same nor the raising and lowering of said wheel; 55 but

What I do claim and desire to secure by Letters Patent is—

1. The device for keeping the wheel in gear while raising and lowering and the 60 combination of the radius bar and the sliding carriage which carries the shafts of the pinions and also moves the miter wheels which slide on the feathered shafts, as this device and this combination of well known 65 mechanical devices is my own invention and has enabled me to keep the excavating wheel always in gear with the engine and has never been so applied before.

2. I claim as my invention the self acting 70 latch, F, in its particular form and mode of adjustment, it being so shaped and adjusted as to hold on to the lid of the bucket until it is struck by the tipper and so balanced that by its own gravity it will fall over and 75 latch again before the bucket enters the water this particular form and adjustment with the pin marked H does away with the necessity of springs and is the result of careful and expensive experiments. 80

I also claim that particular combination of chutes or sluice ways G, G, which form an apex under the discharging tipper and pass athwartships on an incline toward the scows, which particular combination has enabled me to discharge an excavating 85 wheel laterally on either or both sides.

CHS. H. FONDÉ.
